Primary Examiner — Lucy Lieberman

(74) Attorney, Agent, or Firm — Clifford W. Browning;
Krieg DeVault LLP(57) CLAIM

The ornamental design for a watch case, as shown and described.

DESCRIPTION

FIG. 1 is a front view of the watch case of the present invention.

FIG. 2 is a rear view of the watch case of FIG. 1.

FIG. 3 is a right side view of the watch case of FIG. 1.

FIG. 4 is a left side view of the watch case of FIG. 1.

FIG. 5 is a bottom view of the watch case of FIG. 2.

FIG. 6 is a top view of the watch case of FIG. 1; and,

FIG. 7 is a perspective view of the watch case of FIG. 1.

The broken lines shown on the bottom surfaces of the watch case in FIG. 5 represent portions of the watch case that form no part of the claimed design.
